UNITED STATES PATENT OFFICE.

JOHN W. BOUGHTON, OF PHILADELPHIA, PENNSYLVANIA.

AIRSHIP.

1,304,654.

Specification of Letters Patent. Patented May 27, 1919.

Application filed July 15, 1916. Serial No. 109,502.

To all whom it may concern:

Be it known that I, JOHN W. BOUGHTON, a citizen of the United States, residing in the city and county of Philadelphia, State of Pennsylvania, have invented a new and useful Airship, of which the following is a specification.

My invention consists in providing an air ship with means for changing the angularity 10 of the propeller or propellers thereof for purposes requiring the same.

It consists also of the construction of the propeller supporting member whereby it is light and strong and furthermore braced to 15 increase its strength.

It consists also of means for causing the various shafts employed to run with ease, with less friction, greater uniformity and less noise than heretofore.

20 It consists also of details of construction as will be hereinafter set forth.

The invention is satisfactorily illustrated in the accompanying drawing, but the important instrumentalities thereof may be varied, and so it is to be understood that the invention is not limited to the specific details shown and described.

Figure 1 represents a perspective view of an air ship embodying my invention.

30 Fig. 2 represents a partial plan view, and partial horizontal section of detached portions on an enlarged scale.

Fig. 3 represents a perspective view of one of the planes of the ship and its operative mechanism.

Fig. 4 represents a partial side elevation and partial section of portions of the gearing employed for changing the angle of the propeller of the ship.

40 Fig. 5 represents a section of a portion on line 5—5 Fig. 2.

Fig. 6 represents a front elevation of a portion of the ship.

Fig. 7 represents a plan view of a portion 45 of Fig. 6 on an enlarged scale.

Fig. 8 represents a partial side elevation and partial section of a modification of gearing employed.

50 Fig. 9 represents a longitudinal section of a portion of a pontoon employed.

Similar numerals of reference indicate corresponding parts in the figures.

The present application is a continuation in part of my prior application Serial No. 55 584,656 and of another application Serial No. 14,641.

Referring to the drawings.

1 designates the frame of the air ship, and 2 designates a cabin mounted thereon, said cabin being provided with port holes 3 for 60 the guns 4 which are supported in the cabin in any suitable manner, said cabin being also adapted to contain cannoneers, passengers, supplies, etc.

Rising from the front of the frame above 65 said cabin are the standards 5, on which is mounted the forward end of the horizontally arranged plane 6 which is adapted to turn or swing on said standards and so change its angularity as desired. In order 70 to operate said plane there are connected pivotally with the rear end thereof the links 7, the lower members of the end ones which are pivotally mounted on the shaft 8 which is secured in the hanger 9, the central one having 75 rigid connection with said shaft, the said hanger depending from the shaft 10 of the swinging plane 6, the lower member of the central link 7 having rigidly connected with it the link 11, the forward member of which 80 is passed vertically through an opening 12 in the roof of the cabin and extends into the latter where it is pivotally connected with the lever 13 whose axis 14 is mounted on suitable walls in the cabin, said lever carrying 85 the latch or dog 15 whose point is adapted to enter either of the teeth of the toothed sector 16 which is secured within the cabin, it being seen that when said dog 15 is disengaged from said sector 16 the lever 13 may 90 be moved, whereby the connected links and rock shaft may raise or lower the rear end of the plane 6 and so adjust the latter in desired angularity, after which the dog is engaged with the respective tooth of the sector, 95 and so the plane is controlled in its adjustment.

It will be seen that a plane and its operating mechanism may be applied to the rear portion of the frame or other portion thereof of thus providing a plurality of planes for the ship.

17 designates the propellers of the ship, the same being respectively at the fore and aft of the frames 18, said frames being on 105 opposite sides of the cabin and being duplicated at the bow and stern portions of the ship.

The frames 18 are of skeleton form whereby they are light in structure and 110 pointed at their front and rear ends so as to easily penetrate the air, their sides 19

being connected by the transverse bars 20 for strengthening said frame.

The propellers are connected each with a longitudinally-extending shaft 21 which has ball bearings 22 on heads 18* on the respective end of the frames 18, said shafts having also ball bearings 23 on the cross bars 20 of the frames 18. The shafts 21 of each frame are geared together by the pinions 24 and 25, the pinions 25 being secured to the driving shaft 26 which has ball bearings on heads 27 in the respective sides of the frame 18, said shaft receiving power by suitable mechanism 28 from the engine 29 of the ship, it being evident that said power is transmitted to the propellers 17 so that the latter are properly rotated for the propulsion of the ship.

The driving shaft 26 has ball bearings on the upright members 30. Keyed or otherwise connected with the heads 27 of the frames 18 by the collars 31 on said heads and bolts 32 are the sleeves 33, said bolts passing through the latter and tightening on said collars, the side portions of the driving shaft 26 passing freely through said sleeves. The outer terminals of the sleeves 33 have ball bearings 34 on the adjacent portions of the driving shaft 26, it being evident that the several shafts named may run with ease and precision and comparatively noiseless on their bearings, it being noticed also that the driving shaft 26 has ball bearings.

Secured to the inner ends of the sleeves 33 are the caps which carry the toothed sectors 37, the teeth whereof are of the order of the segment of a worm wheel, and engaging them are the worms 38 each of whose shafts 39 is mounted in bracket 40 on the adjacent portion 41 of the frame 1 of the ship, said shaft being geared over to the shaft 42 by the intermediate pinions 43, said shaft 42 being geared over to the hand wheel 44 by the intermediate pinions 45.

It will now be seen that by operating the wheel 44 motion will be communicated by the intermediate mechanism to the sleeves 33, and consequently to the frames 18 whereby said sleeves and frame turn on the driving shaft 26 and so change the angles at which the propellers may be presented to the atmosphere for purposes requiring the same, without, however interfering with said driving shaft and the rotation of the propellers.

In order to truss or brace the frames 18 in their connection with the sleeves 33 there are secured to the ends of said frames the caps 46 from which extend the tie-rods 47, the latter being connected with plates 48 on the outer terminals of the sleeves 33, each tie-rod being formed in sections which are connected with buckles 49 whereby the rod may be adjusted and tightened, it being evident that the tie rods stiffen and brace the

frames 18 on opposite sides thereof forming a strong structure.

It will be noticed in Fig. 2 that one of the plates 48 is braced against the outer side of the cap 36 so as to receive the inward thrust of the tie rods for strengthening purposes so the adjacent ends of the tie rods require to pass through the sector 37. For this purpose the body of said sector is cut away or formed with the opening 50, therethrough, see Fig. 4, the width of said opening being sufficient to allow the sector to be rotated in either direction without interference of the tie rods, as the extent of rotation of the sector is limited.

In Fig. 8 I show a worm and worm wheel gearing 51 intermediate of the hand wheel 44 and shaft 42 for operating the latter in lieu of the bevel pinion gearing 45, in Fig. 7.

On the left side of Fig. 7 I show a plurality of bevel pinions 52 connected with the thimble 52* which is feathered on the shaft 42 whereby said pinions 52 may be moved to and from the bevel pinion 43 on the left hand shaft 39, and thus the opposite sleeves 33 in which the driving shaft 26 is contained may be rotated in same direction, or in reverse direction, so that in the position of parts as shown in said Fig. 7, both propellers may be made to assume at one time the same angularity, but in another case, it may be necessary to lower one of the propellers and raise the other propeller, in which latter case the thimble 52* is shifted whereby the left hand pinion 52 is thrown in gearing with the left hand pinion 43, and so the left hand shaft 39 is reversed in rotation by the hand wheel 44, but the pinion 43* on the right hand end of the shaft 42 remains in gear with the adjacent pinion 43, and thus the shaft 39 on the right side of Fig. 7 may be rotated in the direction as before by said hand wheel 44, and so said sleeves 33 receive rotation in reverse directions, and the shafts of the propellers are raised or tipped in reverse directions.

On the neck of the thimble 52* is freely fitted one end of the rod 53 whose outer end is pivotally connected with the lever 54 which is mounted on the toothed sector 55, the latter being secured to a proper portion of the frame 1 and being adapted to have said lever locked so as to retain the thimble 52* and its pinions in their set position.

In order to strengthen the portion of the frame that supports the cabin and adjacent members of the ship, I employ the transverse beam 56 and the struts 57, which latter are interposed between the floor 58 and said beam 56, forming a strong truss for the purpose stated.

In Fig. 3 I show in dotted lines an incasement for the members at and about the center of the swinging frame 18 for receiving a suitable lubricant for said members.

The frame of the ship has pontoons 59 connected therewith for the purpose of flotation in the event of the ship alighting on water, said pontoons being formed in sections closed one from the other, so that if one section is fractured or destroyed the other sections will be sufficient for floating the ship.

Having thus described my invention what I claim as new and desire to secure by Letters Patent, is:—

1. In an air ship, a propeller, a swinging frame on which the shaft of said propeller is mounted, heads on the ends of said frame, sleeves connected with the sides of said frame, a driving shaft in said sleeves and frame, gearing for said driving shaft and propeller shaft, and tie-rods extending from the end heads of said frame to the outer terminals of said sleeves and connected therewith.

2. In an air ship, a propeller, a swinging frame on which the shaft of said propeller is mounted, heads on the ends of said frame, sleeves connected with the sides of said frame, a driving shaft in said sleeves and frame, gearing for said driving shaft and propeller shaft, tie-rods extending from the end heads of said frame to the outer terminals of said sleeves and connected therewith, and means for adjusting the tension of said tie-rods.

3. In an air ship, a propeller, a swinging frame on which the shaft of said propeller is mounted, a driving shaft on said frame geared with the propeller shaft, sleeves connected with the sides of said frame, said driving shaft occupying said sleeve, mechanism for turning said frame, a motor for

operating said driving shaft, plates on the outer terminals of said sleeves, and tie-rods connected with said plates passing freely through said mechanism and connected with said frame.

4. In an air ship, a propeller, a swinging frame on which the shaft of said propeller is mounted, a sleeve connected with said frame, a driving shaft in said sleeve and frame, intermeshing gearing on said driving and propeller shafts, a motor for said driving shaft, and gearing including a rotatable toothed member adapted to turn said sleeve and consequently said frame, and a tie-rod connected with said frame and sleeve, said toothed member being adapted to have said tie-rod pass freely through the same.

5. In an air ship, a driving shaft mounted thereon, frames on opposite sides of the ship swingingly mounted on said shaft, propellers mounted on said frames and geared with said shaft, sleeves connected with said frames and adapted to be mounted on said shaft, a motor, means for communicating the power of said motor to said shaft, a countershaft, a hand controlled device for operating the latter, shafts intermediate of said countershaft and sleeves, and intermeshing gearing for said shafts, certain of said gearing being shiftable, and hand controlled means for operating the shiftable gearing whereby the direction of rotation of said sleeves may be in unison in the same direction, or in reversed directions independently of each other.
